US00D995296S

(12) **United States Design Patent** (10) **Patent No.:** **US D995,296 S**
Trovaag et al. (45) **Date of Patent:** **** Aug. 15, 2023**

(54) **BLANK FOR PACKAGING CONTAINER**(71) Applicant: **Elopak AS**, Spikkestad (NO)(72) Inventors: **Ole-Petter Trovaag**, Heggedal (NO);
Madeleine Kristin Wieser, Vettre (NO); **Ivica Franic**, Oberwaltersdorf (AT)(73) Assignee: **Elopak AS**, Spikkestad (NO)(***) Term: **15 Years**(21) Appl. No.: **29/803,123**(22) Filed: **Aug. 10, 2021****Related U.S. Application Data**

(62) Division of application No. 35/509,441, filed on Apr. 16, 2019 (U.S. filing date under 35 U.S.C. 384), and having an international filing date of Apr. 16, 2019, now Pat. No. Des. 935,880.

(30) **Foreign Application Priority Data**

Oct. 19, 2018 (EM) 005803277-0002
